[57] ABSTRACT

A magnetic system for relays, particularly poled relays, wherein at least one pole shoe covering a portion of a pole surface of a permanent magnet guides the magnetic flow of a particular region of the magnet primarily through a main armature, while the magnetic flow from another particular region of the permanent magnet is guided primarily by way of an auxiliary armature.

MAGNETIC SYSTEM FOR RELAYS

BACKGROUND OF THE INVENTION

1. Field of the Invention

This invention relates to a magnet system for a poled relay having two stable switching positions, an electromagnetic excitation winding and at least one permanent magnet for maintaining the respective electrically provided armature position, wherein the magnetic current resulting from the superposition of permanent magnetic current and excitation magnetic current becomes effective partially by way of a main armature and partially by way of an auxiliary armature.

2. Description of the Prior Art

Poled relays of the general type mentioned above usually exhibit a problem of adjusting the energy of the permanent magnet for holding the main armature and the auxiliary armature and the respective spring force of the contact springs in such a way that the desired current values are respectively obtained for attraction excitation and for drop excitation. In the case of relays which have been designed for a certain number of contacts a given ratio of the attraction forces for the main and auxiliary armatures can be obtained relatively simply by means of a corresponding construction and by means of applying permanent magnets of a particular strength. However, even in such cases material and production tolerances will occur which sometimes require an adjustment of the permanent magnet.

In order to be able to utilize a relay in as varied number of applications as possible, however, a magnet system is desired which, depending upon the particular application requirements, can be provided with a more or less large number of spring sets without requiring a change of construction. In this instance, the holding power in the stable positions of the relay must be adjusted to the respectively effective spring forces in a poled relay. Since the springs are often biased in such a way that they oppose the armature force in one switching direction, but cooperate with the armature force in the other switching direction, the respective holding power of the permanent magnet in the two stable positions must be different for the greater number of spring sets which may be utilized in a relay. Since, on the other hand, a single permanent magnet is often provided due to construction and economic reasons, and the single permanent magnet must provide the holding power for both stable positions, the problem arises of rendering the magnetic forces for the main armature and auxiliary armature effective in a different manner.

The German Letters Pat. No. 1,188,455 discloses the provision of adjusting the holding power poles of the main armature and of the auxiliary armature independently of each other for an electromagnetic relay. In this prior art arrangement, the adjustment is effected by means of changing the air gap at the auxiliary armature, for example, by means of a mechanical bending operation. This, however, means that two operational processes are required for adjusting the relay. First of all, the holding magnetic force itself must be balanced in order to attain an adaptation of the permanent magnet to the number of contacts and in order to attain a balance of tolerances. Only after this first operational process is accomplished is the adjustment of the ratio between the magnetic forces at the main armature and the magnetic forces at the auxiliary armature effected

by means of a mechanical adjustment of the auxiliary armature.

SUMMARY OF THE INVENTION

5 It is the object of the present invention to provide a magnetic system for a poled relay of the type mentioned above which can be adjusted to the desired number of contact spring sets and to the desired ratio between the main armature force and the auxiliary armature force in a single operation by means of balancing the permanent magnet whereby simultaneously production and material tolerances are also balanced.

10 According to the invention, the foregoing object is achieved in such a way that, by means of arranging at least one pole shoe covering a partial pole surface of the permanent magnet or the permanent magnet arrangement, respectively, the magnetic current from a particular partial region of the permanent magnet or the permanent magnet arrangement, respectively, is 15 primarily guided by way of the main armature, and the magnetic current from a particular other partial region is primarily guided by way of the auxiliary armature. In this manner, it is provided that the two magnetic ranges can be adjusted to given values by external magnetic fields, separately from each other. The two regions of 20 a single permanent magnet therefore have the effect of two separate magnets since the magnetic current emerging from these regions have little influence on each other and are therefore essentially independent. 25 Therefore, a construction could include two separate permanent magnets which are arranged beside each other so that they are jointly traversed by the excitation magnetic current. The pole shoe would then cover the pole surface of one of the two permanent magnets and 30 thus cause the same effect as has been described hereinbefore for a single permanent magnet. In the following description, only the more economic construction with a single permanent magnet is particularly set forth and it should therefore be appreciated that two separate permanent magnets could be employed for the 35 equivalent function.

40 In a preferred embodiment of the invention, a permanent magnet is arranged above a pole piece of the excitation coil and polarized in the direction of the coil access. Hereinafter the magnetic currents will be simply referred to as currents and should not be confused with the electrical current which traverses the excitation coil. The excitation coil can be enveloped in a U-shaped yoke whose central portion partially covers a pole surface of the permanent magnet as a pole shoe. Furthermore, an auxiliary pole plate constructed of soft magnetic material can be arranged between the core of the excitation coil and the permanent magnet. A favorable 45 construction of the magnetic system according to the invention is realized wherein the main armature forms a respective operational air gap with the free end of the coil core and with the yoke. The auxiliary armature is therefore advantageously arranged at approximately a right angle with respect to the main armature so that it, in turn, forms operational air gaps with the permanent magnet and with the auxiliary pole piece. According to 50 this invention, it is also favorable if the main armature and the auxiliary armature are constructed as a single piece.

55 In the construction of a further development of the invention, it is provided that two separate pole shoes be arranged above the permanent magnet, one of the pole

shoes being connected in a magnetically conductive relationship with the yoke and the other defining an air gap with the auxiliary armature. In this embodiment, the separation of the permanent magnet into two ranges which are independent of each other to a great degree is particularly well expressed. In the place of the second pole shoe, the auxiliary armature can be shaped in such a way that it angularly embraces the corresponding portion of the permanent magnet. Preferably, Strontium oxide is utilized as the material for the permanent magnet, since this material can be magnetized extremely well in the direction of its thickness so that it can be arranged in a favorable manner as a plate shaped part adjacent one pole of the excitation coil without thereby causing excessive dimensions in the direction generally defined by the longitudinal axis of the excitation coil.

BRIEF DESCRIPTION OF THE DRAWINGS

Other objects, features and advantages of the invention, its organization, construction and operation will be best understood from the following detailed description of embodiments thereof taken in conjunction with the accompanying drawings, on which:

FIG. 1 is an elevational view of the basic construction of a magnet system according to the present invention;

FIG. 2 is a perspective view of a magnet system for a practical embodiment of the invention having a U-shaped yoke;

FIG. 3 is an elevational view, in section, of a magnet system having two pole shoes at the permanent magnet;

FIG. 4 is an elevational view, in section, of a magnet system with a pole shoe and an auxiliary armature having a portion which angularly embraces the permanent magnet;

FIG. 5 is an illustration of an arrangement for the magnetic balancing of the permanent magnet particularly showing a magnetic system construction such as illustrated in FIGS. 1 and 2; and

FIG. 6 is an illustration of an arrangement similar to the other magnetic structures, but which utilizes two permanent magnets.

The following description and the corresponding figures of the drawings are only directed to the magnet system for a relay in that one skilled in the art will readily appreciate various mounting configurations for pivoting the armatures and supporting spring contacts.

DESCRIPTION OF THE PREFERRED EMBODIMENTS

In FIG. 1, the basic arrangement of a magnet system according to the present invention and the guidance of the current attained thereby is illustrated. The magnet system comprises a coil 1 wound about a core 2, with a main pole piece 3 disposed at one end thereof and an auxiliary pole piece 4 mounted at the other end thereof. The coil 1 is an excitation coil which is traverse by an electrical current in one direction or the other for producing the attraction and drop excitations of a relay. A permanent magnet 5 is disposed adjacent to the auxiliary pole piece 4 and serves for maintaining the respective armature positions of the relay. The permanent relay 5 is polarized in the direction of the longitudinal axis of the coil 1; thereby, the pole surface which is facing away from the coil 1 or the auxiliary pole piece 4, respectively, is partially covered by a pole shoe 6 which guides a portion of the current from the excita-

tion coil 1 and from the permanent magnet 5 toward the main armature 8 by way of a yoke 7. The main armature 8 is constructed as a single piece with an auxiliary armature 9 and forms an angle of somewhat more than 90° therewith.

The forces affecting the main armature 8 and the auxiliary armature 9 are produced in the four operational air gaps L1 through L4. Since only a portion of the permanent magnet 5 is connected with the yoke 7, by way of the pole shoe 6, it can be magnetically regarded as two parts so that a main permanent magnet part 5a and an auxiliary permanent magnet part 5b can be recognized. The current or flux ϕ_1 which is produced in the main part 5a of the permanent magnet 5 therefore closes to a predominant degree by way of the auxiliary pole piece 4, the core 2, the main pole piece 3, the main armature 8, the yoke 7, and the pole shoe 6. Accordingly, a magnetic force is produced in the main air gaps L1 and L2, between the armature 8 and the main pole piece 3 and the yoke 7, respectively, which affects the main armature 8. The permanent magnet current ϕ_2 , however, which is produced in the auxiliary part 5b of the permanent magnet 5 is guided to the greatest extent to the auxiliary armature 9 by way of the auxiliary pole piece 4, and from there back to the auxiliary part 5b, whereby it bridges the air gaps L3 and L4.

For switching the relay from one stable position into the other, a current ϕ_3 of suitable size and polarity, and which is produced by electrical current flow in the excitation coil 1, is superimposed over the two magnetic currents ϕ_1 and ϕ_2 . Depending on the polarity of this control current ϕ_3 , either the main permanent magnet current ϕ_1 is augmented and the auxiliary permanent magnet current ϕ_2 is weakened, or the opposite occurs so that, due to the resulting magnetic current in the air gaps L1, L2 and L3, either the main armature 8 or the auxiliary armature 9 is attracted.

FIG. 2 illustrates a practical embodiment of a magnet system according to this invention is a perspective illustration. An excitation coil 11 affects a main armature 18 via a main pole piece 13 and an auxiliary armature 19 via an auxiliary pole piece 14. A yoke 17 is designed as a U-shaped element; the central portion of this U-shaped element covers a portion of the pole surface of a permanent magnet 15 as a pole shoe 16. The function of such a magnet system has already been described with reference to the structure of FIG. 1. The difference between these two constructions is seen in the fact that the main armature 18 forms two air gaps with the yoke 17 in the system according to FIG. 2.

FIG. 3 illustrates a magnet system having a U-shaped yoke as in FIG. 2, but with a slightly different construction. A lateral view has been provided in section whereby the individual parts can still be well recognized. The magnet system again comprises an excitation coil 21 having a core 22, a main pole piece 23 and an auxiliary pole piece 24. A permanent magnet 25 is arranged at the auxiliary pole piece 24, and one of its pole surfaces is partially covered and magnetically connected with the yoke 27 by way of a pole shoe 26. In this manner, a portion of the permanent magnet current is extended from the range 25a of the permanent magnet 25 by way of the main armature 28. As opposed to the constructions illustrated in FIGS. 1 and 2, a pole shoe 26a is also provided and arranged to cover and be magnetically connected to a portion of the aforemen-

tioned surface in a second range 25b of the permanent magnet 25. The pole shoe 26a serves to guide the permanent magnet current from the range 25b toward the auxiliary armature 29.

In FIG. 4 a further embodiment of a magnet system according to the invention has been illustrated. This magnetic system is constructed in the same manner as the systems hereinbefore described and has an excitation coil 31, a core 32, a main pole piece 33 and an auxiliary pole piece 34. The permanent magnet current is again guided by way of a pole shoe 36 toward a yoke 37 and thus toward a main armature 38 from a range 35a of a permanent magnet 35, while the current from a range 35b of the magnet 35 closes by way of an auxiliary armature 39. In contrast to the structure illustrated in FIG. 3, a second pole shoe is not provided, however, the auxiliary armature 39 comprises a projection 39a to provide an angular inclination of the armature which embraces at least the oppositely facing portions of the auxiliary part 35b of the permanent magnet 35 and therefore provides an auxiliary air gap with respect thereto.

FIG. 5 illustrates a simple arrangement for the magnetic balancing of a magnetic system according to the present invention. The magnet system illustrated in FIG. 5 is constructed in the same manner as the magnet systems illustrated in FIGS. 1 and 2 and needs no further detail description. By means of coupling a direct magnetic field of suitable strength to the permanent magnet 41, a separate adjustment of two magnetic portions 41a and 41b is possible. For this purpose, a magnet coil 42 having a demagnetizing yoke 43 is applied to the permanent magnet 41 or to the pole shoe 44, respectively, in such a way that the field lines of the demagnetizing field occur in the main part 41a of the magnet 41, due to the pole shoe 44 and closes by way of the auxiliary pole piece 45 and the auxiliary part 41b of the permanent magnet 41 toward the other pole of the yoke 43. When a direct field of the illustrated polarity is applied, the main part 41a of the permanent magnet 41 is weakened. A repoling causes a decrease of the permanent magnet current produced by the auxiliary part 41b. Such a magnetic balancing is also possible with the embodiments of the invention illustrated in FIGS. 2 and 3 and is accomplished in the same manner.

FIG. 6 illustrates a further embodiment of the magnetic system according to the present invention. In the previous figures one permanent magnet was separated into two regions by a pole shoe which only covers part of the pole surface. This internal magnetic separation is now carried out in FIG. 6 by the provision of two permanent magnets 55a and 55b which are arranged spaced side-by-side and parallel to each other and against an auxiliary pole plate 54. The pole surface of one of the two permanent magnets 55a is covered by a pole shoe 56 which is connected with a yoke 57 in a manner similar to that illustrated for the elements 5a, 6 and 7 of FIG. 1.

In addition, the magnetic system of FIG. 6 is constructed similar to the magnetic system according to FIG. 1 in that it comprises an excitation winding or coil 51, a core 52 and a main pole piece 53. A main armature 58 is effective with the main pole piece 53, while an auxiliary armature 59 forms an operational air gap with the auxiliary pole piece 54. A subdivision of the permanent magnet into two separate partial magnets which, however, are arranged parallel to each other

could also be carried out in the same manner with respect to the constructions according to FIGS. 3 and 4.

Although we have described our invention by reference to certain specific illustrative embodiments, many changes and modifications of our invention may become apparent to those skilled in the art without departing from the spirit and scope thereof. We therefore intend to include within the patent warranted hereon all such changes and modifications as may reasonably and properly be included within the scope of our contribution to the art.

We claim:

1. A magnetic system for a relay having two stable switching positions, comprising: coil means for excitation by a direct current of either polarity to produce a respective magnetic current along the direction of the longitudinal axis of said coil means; a main pole at one end of said coil means and an auxiliary pole at the other end of said coil means; permanent magnet means for holding said system in said stable positions, said permanent magnet means having a surface disposed adjacent said auxiliary pole and including an opposite parallel surface defining first and second portions; a yoke disposed adjacent and extending over the length of said coil means, said yoke including a pole shoe partially covering said opposite surface of and magnetically connected to said first portion of said permanent magnet means; and armature means including a main armature and an auxiliary armature, said main armature disposed adjacent said coil means and said yoke and included in a main permanent magnetic circuit which includes said coil means, said first portion of said permanent magnet means and said yoke and said pole shoe, said auxiliary armature disposed adjacent said second portion of said permanent magnet means and included in an auxiliary magnetic circuit which includes said second portion of said permanent magnet means, said permanent magnet means poled to produce magnetic current directions in said main and auxiliary magnetic circuits which are respectively aided and opposed in response to excitation of said coil means by a direct current of a given polarity.

2. A magnet system according to claim 1, wherein said auxiliary pole includes a plate of soft magnetic material disposed between said permanent magnet means and said coil means.

3. A magnet system according to claim 1, wherein said permanent magnet is in the shape of a plate and polarized in the direction of the thickness of the plate and the axis of said coil means.

4. A magnet system according to claim 1, wherein said yoke is U-shaped, said pole shoe being the central leg of the U, and said coil means is disposed between the other legs of the U.

5. A magnet system according to claim 1, wherein said main and auxiliary poles include respective pole pieces and said main pole piece and said yoke define operational air gaps with said main armature.

6. A magnet system according to claim 5, wherein said auxiliary armature is arranged at approximately a right angle with said main armature and defines operational air gaps with said second portion of said permanent magnet and said auxiliary pole piece.

7. A magnet system according to claim 1, wherein said armature means includes a single piece which comprises said main and auxiliary armatures.

8. A magnetic system according to claim 1, wherein said auxiliary pole comprises a pole piece disposed adjacent and defining an air gap with said auxiliary armature.

9. A magnet system according to claim 1, wherein said auxiliary armature includes an angularly shaped portion for embracing said second portion of said permanent magnet means.

10. A magnet system according to claim 1, wherein said permanent magnet means comprises a separate permanent magnet for each of said portions.

11. In a magnet system for a bistable polar relay of the type having a coil with oppositely disposed poles energizable in either direction longitudinally of the coil to place the relay in its respective stable states, and at least one permanent magnet for holding the relay in a stable state, and wherein the magnetic current flow resulting from the superposition of the excitation magnet

current and the permanent magnetic current become effective partially via a main armature and partially via an auxiliary armature; in combination therewith the improvement comprising: at least one pole shoe covering and magnetically connected with only a portion of one pole surface of the permanent magnet and extending to a point adjacent said main armature, whereby the magnetic current flow of a first region of said magnet is guided primarily via the main armature and the magnetic current flow from a second region of said magnet is guided primarily via the auxiliary armature, said permanent magnet poled to produce magnetic current directions in the first and second regions and the associated main and auxiliary armatures which are respectively aided and opposed in response to energization of said coil in a given direction.
